UNITED STATES PATENT OFFICE

2,025,404

SAND CORE FORMING APPARATUS

Albert Stahn, Hanover, Germany

Application June 18, 1934, Serial No. 731,155
In Germany June 27, 1933

2 Claims. (Cl. 22—10)

My invention refers to sand core and mold forming apparatus and more especially to apparatus of the kind described, in which the sand or the like contained in a sand container is supplied to the core box or mold by means of compressed air.

My invention has particular reference to the means for feeding the air to the sand container and it is an object of my invention to provide air feeding means which are more efficient than those hitherto in use.

The container, in which a supply of molding sand or the like is stored, is hitherto supplied with compressed air through an opening or openings in the cover of such container. It is well known to every person skilled in this art, that on admitting compressed air through this opening, cavities or funnel-shaped channels will form in the sand, which extend substantially in a straight line from the air inlet to the sand outlet formed in the bottom of the container. These channels thus follow the path of least resistance. It is equally known that these funnel-shaped channels prevent a considerable part of the sand from being expelled from the container, more especially in the case of sand containing clay or so-called green molding sand, for the compressed air will force the sand against the side walls of the container, and the sand will then stick to these walls, instead of being expelled by the air current. It is for this reason that stirrers have been provided in these containers; however these stirrers require a separate drive consuming energy and are exposed to rapid wear. The use of these and other contrivances has not sufficed to enable the compressed air to expel all of the sand.

The means provided according to the present invention solve this problem in the simplest and most efficient manner without requiring any energy, since the invention utilizes the repulsion effect exerted by the compressed air entering the container on a flexible tube, the free end of which is caused, by this repulsion effect, to continuously change its position relative to the body of sand in the container, so that no distinct channels can be formed therein.

Alternatively, instead of using flexible tubes, I may use rigid tubes movably suspended in the container so as to allow them to move under the repulsion effect exerted on their ends by the compressed air.

In the drawing affixed to this specification and forming part thereof, two embodiments of my invention are illustrated diagrammatically by way of example.

In the drawing,

Fig. 1 is a vertical axial section of a funnel-shaped sand container equipped with a flexible air admission tube.

Fig. 2 is a similar view of a modification, in which the air is admitted through two movably suspended rigid tubes.

Referring to the drawing and first to Fig. 1, 1 is the funnel-shaped sand container, 2 is the cover closing same, 3 is the bottom opening, 10 through which the sand is expelled. 4 is the air inlet pipe extending through an opening in the cover 2 and 5 is a flexible tube fitted to the pipe 4, this tube being a rubber tube, a flexible metal tube, or the like.

In the operation of this device, when compressed air is admitted into the container through the pipe 4 and tube 5, the repulsion effect exerted on the tube will cause this latter to execute jerky movements, whereby the free end of the tube is continuously displaced on the surface of the body of sand in the container, thereby preventing the formation of the funnel-shaped channel indicated in the sand by dotted lines.

In the modification shown in Fig. 2, the inner end of the pipe 4 is branched and to the branch pipes 6 are fitted rigid tubes 7 by means of ball couplings 8, which may also be replaced by other movable coupling means including short rubber tube ends or the like.

Here also, when the compressed air is admitted through pipe 4, the compressed air entering the tubes 7 will cause them to wander above or in the sand, thereby loosening the sand and preventing the formation of a funnel-shaped channel.

Obviously the movable sand admitting means shown and described will direct the compressed air onto ever varying points of the body of sand, thereby preventing any sticking to the walls and the formation of definite cavities or channels. The term "wall" as used in the claims is intended to include the removable cover of the sand container.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:—

1. In an apparatus of the kind described the combination, with a sand container, of a compressed air admission tube passing through and fixed in a wall of said container, the end of said tube, which projects into said container, being free under the repulsion effect exerted on it by the compressed air, to be automatically displaced relative to the sand in the container.
- 5

2. In an apparatus of the kind described the combination, with a sand container, of a flexible compressed air admission tube passing through and fixed in a wall of said container, the end of said tube, which projects into said container, being free under the repulsion effect exerted on it by the compressed air, to be automatically displaced relative to the sand in the container.

ALBERT STAHL.
